DESIGN FOR AN ASH TRAY

Edwin L. Beckwith, West Newton, Mass., assignor
to Beckwith Manufacturing Company, Dover,
N. H., a corporation of New Hampshire

Application April 6, 1946, Serial No. 128,359

Term of patent 14 years

(Cl. D85—2)

To all whom it may concern:

Be it known that I, Edwin L. Beckwith, a citizen of the United States, residing at West Newton, in the county of Middlesex and Commonwealth of Massachusetts, have invented a new, original, and ornamental Design for an Ash Tray, of which the following is a specification, reference being had to the accompanying drawing, forming a part thereof, in which:

Fig. 1 is a plan view of an ash tray showing my new design,

Fig. 2 is an elevational view thereof, and

Fig. 3 is a cross sectional view thereof taken on the line 3—3 of Fig. 1.

I claim:

The ornamental design for an ash tray, substantially as shown.

EDWIN L. BECKWITH.
